UNITED STATES PATENT OFFICE.

ALBERT PRUVER, OF BROOKLYN, NEW YORK.

ARCH-SUPPORT HEEL.

1,249,637.

Specification of Letters Patent. Patented Dec. 11, 1917.

Application filed July 13, 1917. Serial No. 180,701.

To all whom it may concern:

Be it known that I, ALBERT PRUVER, a citizen of the United States of America, and a resident of Brooklyn, county of Kings, and State of New York, have invented certain new and useful Improvements in Arch-Support Heels, of which the following is a specification, reference being had to the accompanying drawings forming a part thereof.

10 My invention relates to shoes and other foot wear, and it has special reference to arch supporting means therefor.

One object of my invention is to provide a simple and effective arch supporting means for boots, shoes, slippers or the like, which may be readily applied to either old or new shoes.

15 Arch supports of various kinds have been hitherto arranged to fit under the arch of the wearer, either set into the shoe or formed into the structure of the shoe itself. Supports of this character are open to a number of well known objections, particularly those which are inserted in old shoes, because they 20 are more or less uncomfortable and are apt to get out of place. Those that are built into the shoes are often expensive and not always effective.

According to my invention I provide a 25 simple and novel heel which may be readily applied to shoes which are either new or old and which supports the weight of the person in such a way as to cause an upward pressure under the arch of the shoe and automatically constitute an arch support.

It furthermore relieves the heel of the wearer, making the shoe more comfortable for marching or walking long distances. In 30 fact, I have found that shoes equipped with my invention relieve the pain in the arch and at the same time prevents blistering and burning at the heel.

In order that my invention may be thoroughly understood I will now proceed to 35 describe the same in the following specification, and then point out the novel features thereof in appended claims.

Referring to the drawings:

Figure 1 is a partial elevation of a shoe, 40 equipped with an arch support, which constitutes an embodiment of my invention.

Fig. 2 is a bottom plan view of the heel which constitutes the arch support and forms a part of the shoe which is shown in Fig. 1.

Fig. 3 corresponds to Fig. 2 and shows a 55 modification of my invention.

Another modification of my invention is shown in Fig. 4 which corresponds to Fig. 1, and shows only a small portion of the shoe.

Special reference may first be had to Figs. 60 1 and 2, in which 10 designates a shoe, 11 the portion of the sole which is under the arch of the wearer, and 12 the heel.

The heel has a wearing plate or lift 13 which may constitute a separate article of 65 manufacture adapted to be attached to old or new shoes, or may be formed integrally with the heel of the shoe as manufactured. It has a narrow transverse flat surface 14, as shown in Fig. 2, and a flat inclined or 70 beveled surface 15 which is at an angle to the flat surface 14.

The arrangement is such that the weight 75 of the wearer in standing on a horizontal surface, falls on the flat portion 14 which is under the arch of the wearer. In other words, the beveled portion 15 is cut away so that the weight is not supported directly under the heel and consequently when the 80 heel and the ball of the foot of the wearer are pressed down by his weight, the forces are applied on opposite sides of the support which therefore tend to push the sole section 11 upwardly and support the arch of the wearer.

The flat portion 14 may be narrower on 85 one edge than on the other if desired, and this arrangement is illustrated in Fig. 3, the portion 16 being narrower at one side of the heel than at the other, the wider part being 90 preferably on the inside.

By making the flat portion 16 tapering in form, the pressure due to the weight may be concentrated at the narrower part and the arch supporting action thereby increased at 95 one side to a greater extent than at the other. The requirements of the wearer will determine whether the narrower part is located on the inside of the shoe or on the outside.

The surfaces 14 and 15, or 16 and 15 may 100 be joined by a round or curved surface 17, as shown in Fig. 4, if desired.

The heel as above indicated, may be made up as a separate article of manufacture, capable of attachment to either old or new 105 shoes, and it may furthermore be made of leather, rubber, fiber or any suitable material.

The beveled surface of the heel may be at any suitable angle to the flat surface and its inclination is preferably chosen so that it strikes the surface of the ground or floor 5 squarely as the wearer naturally walks. By this means the usual shock due to the sharp edge of the heel striking the ground is avoided.

Modifications in size and details may be 10 made within the spirit and scope of my invention, and I intend that no limitations be imposed other than those indicated in the appended claims.

What I claim is:

15 1. An arch supporting heel for shoes or the like comprising a heel member having a horizontal supporting surface tapered in width across the front of the heel and a

beveled surface at an angle to the horizontal surface.

2. An arch supporting heel for shoes or the like comprising a heel member having a supporting surface decreasing in width from the inside across the heel at the front, and a cut-away surface to throw the weight 25 of the wearer on the supporting surface.

3. An arch supporting heel for shoes or the like comprising a heel member having a horizontal supporting surface decreasing in width from the inside across the heel at the 30 front, and a beveled surface at an angle to the horizontal surface.

In witness whereof, I have hereunto set my hand this 10th day of July, 1917.

ALBERT PRUVER.
